(57) **CLAIM**

The ornamental design for a lantern, as shown and described.

DESCRIPTION

The claimed lantern is used for supplying illumination.

FIG. 1 is a front elevational view of a lantern showing my new design;

FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof;

FIG. 7 is a perspective view thereof;

FIG. 8 is a perspective view thereof with the hanger being pulled out from the handle; and,

FIG. 9 is a front elevational view thereof with the handle being pushed to the middle of the lantern body and turned upside down with the hanger pulled out for hanging.
